UNITED STATES PATENT OFFICE

JAMES S. THOMPSON, OF NEW ROCHELLE, NEW YORK, ASSIGNOR TO FIREBAR CORPORATION, OF CLEVELAND, OHIO, A CORPORATION OF DELAWARE

GRATE CONSTRUCTION

Application filed February 25, 1930. Serial No. 431,283.

This invention relates to grate constructions of the type used in locomotives, marine boiler furnaces and for other similar heavy duty purposes. More specifically, the invention is concerned with a grate made up of a grate frame and grate bars supported therein, the frame being so constructed that fuel supported on it is properly consumed.

In my co-pending application Serial No. 431,282 filed February 25, 1930, I have set forth the difficulties involved in the use of grates as at present constructed, these difficulties arising from the failure on the part of the builders to appreciate that the top of the grate frame serves as a fuel support equally with the grate bars. In the usual grate frame of present construction, the total area of the top of the frame may represent as much as 15% of the total inside cross-section of the fire box, and since the frame is a solid structure and its top has no provision for the passage of air to the fuel supported thereon, the result is that about 15% of the fuel bed receives an insufficient supply of air, burns sluggishly with incomplete combustion, forms clinkers and generally represents a loss.

In the application referred to, I have disclosed and claimed a novel grate construction by which these difficulties may be avoided. The present invention is based on the same principles as that of the application, but differs therefrom in constructional details, these differences affording certain advantages over the other construction in the manufacture of the new grate.

The present grate includes a grate frame provided with the usual grate bar supports, which ordinarily take the form of trunnion sockets for the reception of the trunnions on the ends of the bars. Between these sockets, the frame is cut away to form depressions, in which are mounted removable units which constitute the fuel-supporting parts of the frame. Each unit is formed with a multiplicity of small fuel-supporting areas at its top, communicating with upward air passages along the faces of the units, these passages being defined by spaced lugs on the units. In a side frame member, there is a

single unit in each depression, while in a centre frame member, two units are placed face to face in a depression. The units project above the top of the frame member, so that the latter is substantially out of contact with the fuel, and the units and member are thoroughly cooled at all times by the flow of air through said passages.

For a better understanding of the invention, reference may be had to the accompanying drawings in which

Fig. 1 is a view in side elevation of a grate frame member constituting a part of my invention;

Fig. 2 is a fragmentary plan view of a part of a grate constructed in accordance with my invention;

Fig. 3 is a view in side elevation and partly in section showing a part of the frame member illustrated in Fig. 1 with a fuel-supporting unit in place therein;

Fig. 4 is a plan view partly in cross-section of the parts shown in Fig. 3; and

Fig. 5 is a sectional view on the line 5—5 of Fig. 3.

Referring now to the drawings, the grate is illustrated as consisting of a frame made up of side members 10 of which only one is shown, a center member 11, and a plurality of grate bars 12 mounted between the center member and one of the side members. There are two or more groups of grate bars in the grate depending on the size of the latter, and the bars of each group are connected together by a common shaker rod so that they can be shaken in unison in accordance with standard practice. The bars are provided with trunnions 13 received in trunnion sockets 14 in the tops of the frame members and the center frame member is sufficiently wide so as to receive trunnions of a pair of bars in alignment and lying on opposite sides of the member. The bars I prefer to employ in the new grate are of the form shown in the co-pending application of Buckley, Serial No. 338,352, filed February 8, 1929, although standard bars may be used if desired. The Buckley bar consists of a carrier member 15 and a plurality of fuel-supporting cross-bars 16,

these cross-bars being removable from the carrier member.

The top of each member of the frame is cut away between the trunnion sockets to form depressions generally designated 17 and in the outer walls of each trunnion socket are slots 18. The socket and the depression are outlined by a strengthening rib 19. Received in the slots in a centre member and supported 5 on the lower wall of the depression is a pair of fuel-supporting units 20, while in the side frame members there is one such unit similarly mounted.

Each unit consists of a plate 21 on opposite faces of which are placed lugs 22, the spaces 23 between the lugs providing passages for the upward flow of air. Each lug terminates at its top in a projection 24 which is sub-divided by air channels 25 into a plurality of small fuel-supporting surfaces 26. In the construction shown there are four such surfaces on the upper end of each projection, these surfaces being separated by intersecting channels one of which communicates with the air passages 23. On certain of the lugs are spacing projections 27 which extend out beyond the surfaces of the lugs a short distance.

Each end of each unit is cut away as indicated at 28 so that a pair of units may be inserted in the slots 18 between adjacent trunnion sockets and lie snugly in place with their spacing projections 27 abutting. In order to hold the lower ends of the pairs of 30 units against displacement, they may, if desired, be connected by a bolt 29.

The units are readily inserted in place in the frame and removed so that the main members of the frame free of the units can be 40 first placed in position in the fire box and then the units installed thereafter. Since the units constitute a substantial part of the weight of the frame, their feature of removability makes it possible for the workmen to 45 handle the main frame members with much greater ease than would otherwise be the case and since the weight of this main member is reduced, the likelihood of breakage in shipment and handling is also lessened.

50 It will be observed that in the new frame the fuel-supporting units extend upwardly above the top of the trunnion sockets and thus practically all of the main frame casting is protected against being burnt out. The fuel supported on these units is in contact only with a multiplicity of small surfaces and air may flow on all sides of each projection 24 so that the projection is continually kept cool 55 and the fuel thereon receives the desired air supply. Air may pass up through passages 23 on the outer face of each unit 20 and may also pass upwardly to the fuel bed through passages between a pair of units in a pocket.

60 The new frame affords advantages similar

to those made available by the construction disclosed in my co-pending application above-identified, together with the additional advantage that in the present form the grate frame may be made with greater ease and at 70 less cost.

What I claim:

1. A grate frame which comprises a web having spaced trunnion sockets and depressions between the sockets in its upper edge, a 75 flange outlining said sockets and depressions and provided with slots in the opposite walls of each depression, and fuel-supporting units in said depressions, each unit having a projection at its lower end resting on said flange at the bottom of the depression, the units being spaced from said flange elsewhere in the depression and the ends of said units being received in said slots.

2. A grate frame which comprises a web 80 having spaced depressions in its upper edge and a flange outlining said depressions, a pair of spaced plate-like fuel-supporting units mounted in each depression and resting on said flange, and means connecting the lower 90 end of said units.

3. A grate which comprises a frame having spaced depressions in its top, a pair of fuel-supporting units lying face to face in each depression, means carried by said units for holding them in spaced relation, and means on said frame engaging the ends of each pair of units to prevent their dislodgment from the depression in which they are mounted.

4. A grate frame which comprises a frame 95 member having its top formed with a plurality of depressions, each including a supporting surface, and trunnion sockets between adjacent depressions, the opposite walls of 100 each depression having a slot defined by flanges, and a fuel-supporting unit in each depression resting on said surface by means of an extending lug and spaced above the bottom of said depression elsewhere, said unit 105 having its ends in said slots at opposite ends 110 of the depression and held in place by its own weight.

5. A grate frame which comprises a web 115 having spaced trunnion sockets in its upper edge and depressions between the trunnion sockets, and a flange outlining said depressions, a pair of spaced plate-like fuel-supporting units mounted in each depression and resting on said flange, and means connecting the lower ends of said units.

6. A grate which comprises a frame having spaced trunnion sockets in its upper edge and depressions between the trunnion sockets, a pair of fuel-supporting units lying face to face in each depression, means carried by 125 said units for holding them in spaced relation, and means on said frame engaging the ends of each pair of units for preventing their dislodgment from the depression in which they are mounted.

7. A grate frame having spaced depressions in its upper edge, the opposed end walls of each depression having downwardly extending slots open at the tops thereof, a pair of parallel fuel-supporting units in each depression lying face to face, with their end portions entering said slots, each unit having a

downwardly projecting lug at its bottom on which the unit rests, said lug raising the bottom of the unit above the bottom of the depression, and means on said units for maintaining them separated. 70
